US0D1089215S

(12) **United States Design Patent** (10) **Patent No.:** **US D1,089,215 S**
(45) **Date of Patent:** **** Aug. 19, 2025**

(54) **COMPUTER MAINFRAME**

(71) Applicant: **Lenovo (Beijing) Limited**, Beijing (CN)

(72) Inventors: **Shuai Guo**, Beijing (CN); **Zhe Yang**, Beijing (CN)

(73) Assignee: **Lenovo (Beijing) Limited**, Beijing (CN)

(**) Term: **15 Years**

(21) Appl. No.: **35/522,023**

(22) Filed: **Jul. 29, 2024**

(80) **Hague Agreement Data**

Int. Filing Date: **Jul. 29, 2024**

Int. Reg. No.: **DM/239216**

Int. Reg. Date: **Jul. 29, 2024**

Int. Reg. Pub. Date: **Aug. 23, 2024**

(30) **Foreign Application Priority Data**

Jan. 29, 2024 (CN) 202430059669.2

(57) **CLAIM**

The ornamental design for a computer mainframe as shown and described.

DESCRIPTION

1. Computer mainframe

1.1 : Front

1.2 : Back

1.3 : Left

1.4 : Right

1.5 : Top

1.6 : Bottom

1.7 : Top side perspective view

1.8 : Left side perspective view

1.9 : Back side perspective view

1.10 : Partially Enlarged back side perspective view

The broken lines shown in the drawings illustrate portions of the computer mainframe that form no part of the claimed design. The double dot-dash lines are for the purpose of illustrating a partially enlarged view and form no part of the claimed design.

1 Claim, 10 Drawing Sheets
